UNITED STATES PATENT OFFICE

LOUIS ALEXANDRE CADORET, OF PAWTUCKET, RHODE ISLAND

SHUTTLE THREADER

Application filed July 17, 1930. Serial No. 468,714.

The invention relates to threading devices for the shuttles of automatic looms, and in addition to embodying means for automatically threading the shuttle, includes novel provision for holding the thread under proper tension.

It is the object of the invention to provide an exceptionally simple and inexpensive construction, one which may be quickly and easily applied to a shuttle, and one which will be highly efficient and long-lived.

With the foregoing in view, the invention resides in the novel subject matter herein-after described and claimed, description being accomplished by reference to the accompanying drawings.

Fig. 1 is a top plan view of a portion of the shuttle equipped with the invention.

Fig. 2 is a longitudinal sectional view substantially on line 2—2 of Fig. 1.

Fig. 3 is a horizontal sectional view partly in elevation, the sectional portion of the view being cut on line 3—3 of Fig. 2.

Figs. 4 and 5 are sectional views on lines 25 4—4 and 5—5 of Fig. 3.

Figs. 6 and 7 are perspective views of the threader and tensioner separate from the shuttle.

A preferred construction has been illustrated and will be specifically described, but attention is invited to the fact that within the scope of the invention as claimed, variations may be made.

The device embodies a horizontally elongated vertical wall 10 having its front portion outwardly thickened as illustrated at 11. The front face 12 of this thickened wall end, is acute to the inner longitudinal side 13 of the wall 10 and is also acute to the top of said wall, its lower portion being appropriately rounded to prevent injury to the thread. Between its inner and outer sides, the thickened wall portion 11 is provided with a recess 15. A thread slot 16 formed vertically in the wall, leads from the recess 15 through the inner side 13 of said wall, and a second vertical thread slot 17 extends from said recess to the outer side of the thickened wall end 11. The portion 18 of this thickened wall end, in front of the recess 15 and the

slots 16 and 17, is longer than the portion behind said recess and slots and extends slightly below the upper face of a bottom plate 23 hereinafter described, said portion 18 being in advance of the front end of said plate 23 to provide an entrance throat 19 through which thread sliding down the face 12, may enter the recess and slots. To prevent the thread from cutting the slot walls, any or all of the latter may be provided with 55 steel or other hard wearing pins 20.

Disposed vertically in the recess 15, is a pin 21 of such metal as to resist cutting by the thread, and slideable as well as rotatable upon this pin, is a hard thread tensioning 60 bead 22. When the thread is rather slack, the bead is at its lowermost position but when said thread is more taut, the bead occupies a raised position. The thread is prevented from whipping forwardly out of engagement with the bead 22 by the nose or the like 65 18. Obviously, the pin may be secured in any desired way and any appropriate provision may be made for inserting the bead 22 into the recess 15. In the present showing, the slot 17 is of sufficient width to allow such insertion of the bead.

The bottom plate 23 is preferably integral with the wall 10 and closes the lower end of the recess 15, said plate being adapted to rest 70 upon the bottom of the usual shuttle recess 24 in which the invention is secured by the screw or pin 25.

A top plate 26, preferably integral with the wall 10, projects laterally inward from the latter and is provided with an oblique front end 27 which is flush with the face 12. The free longitudinal edge portion of this top plate 26, is formed with a notch 28, and in front of and behind this notch, said edge 75 portion is turned downwardly and inwardly to provide thread-guiding curls 29 and 30 respectively, the curl 30 being relatively short.

When the threader is installed, it operates as follows:—When the loom doffs and the shuttle makes its first trip along the lay, in the direction of the arrow A (Fig. 1), the thread T whips as it withdraws from the filling F, and in so doing, said thread whips into engagement with the curls 29 and 30. Upon 80 85 90 95 100

the next stroke of the shuttle, in the direction indicated by the arrow A' of Fig. 1, the thread slides down the face 12 and withdraws from the front curl 29, remaining however 5 in engagement with the rear curl 30. When the downwardly sliding thread reaches the throat 19, it enters the slots 15 and 16 and extends across the recess 15, under the thread-tensioning bead 22. During operation of the 10 shuttle after the thread reaches this position, the bead 22 rises and falls according to the pull or tension on the thread and consequently exerts a proper braking influence upon said thread, insuring the best weaving results.

While the exact details disclosed may be advantageously followed, attention is again invited to the fact that within the scope of the invention as claimed, variations may be 20 made.

I claim:—

1. In a shuttle thresher, a vertical wall, outwardly thickened at its front end, the front face of said thickened end being at an 25 acute angle to the inner side of said wall and at an acute angle to the top of said wall, said thickened wall end having a recess, a vertical thread slot from said recess through the inner side of said wall and a vertical thread slot 30 from said recess through the outer side of said thickened wall end, the portion of the latter in front of said recess and said slots terminating sufficiently above the bottom of 35 the thresher to allow entrance of thread into the recess and slots, and thread-tensioning means confined within said recess.

2. In a shuttle thresher, a vertical wall outwardly thickened at its front end, the front face of said thickened end being at an 40 acute angle to the inner side of said wall and at an acute angle to the top of said wall, said thickened wall end having a recess, a vertical thread slot from said recess through the inner side of said wall and a vertical thread slot 45 from said recess through the outer side of said thickened wall end, a bottom plate joined to said wall and closing the lower end of said recess, said bottom plate terminating slightly behind the portion of said thickened wall 50 end in front of said recess and having its upper face above the lower extremity of said portion, a vertical pin mounted in said recess, and a thread-tensioning bead slideable and rotatable on said pin.

3. In a shuttle thresher, a vertical wall outwardly thickened at its front end, the front face of said thickened wall end being at an acute angle to the inner side of said wall and at an acute angle to the top of said wall, said 60 thickened wall end having a recess, a vertical thread slot from said recess through the inner side of said wall and a vertical thread slot from said recess through the outer side of said thickened wall end, the portion of 65 the latter in front of said recess and said slots

terminating slightly above the bottom of the thresher to allow entrance of thread into the slots and recess, thread-tensioning means in said recess, and a top plate projecting laterally inward from said wall and having 70 thread-receiving and guiding means.

4. In a shuttle thresher, a vertical wall outwardly thickened at its front end, the front face of said thickened wall end being at an acute angle to the inner side of said wall and at an acute angle to the top of said wall, said thickened wall end having a recess, a vertical thread slot from said recess through the inner side of said wall and a vertical thread slot 75 from said recess through the outer side of said thickened wall end, a bottom plate joined to said wall and closing the lower end of said recess, said bottom plate terminating slightly behind the portion of said thickened wall end in front of said recess and having its upper face slightly above the lower extremity of 80 said portion, a top plate joined to said wall and projecting laterally inward therefrom, said top plate having an oblique front end flush with said front face of said widened 85 lug end, the free longitudinal edge portion of said top plate having a notch between its ends and being curled downwardly and inwardly in front of and in rear of said notch to provide thread guides, and thread tensioning means confined within the aforesaid recess.

In testimony whereof I affix my signature.
LOUIS ALEXANDRE CADORET.
